SHOE CONSTRUCTION

James F. Marshall, Auburn, N. Y.

Application December 20, 1934, Serial No. 758,380

14 Claims. (Cl. 36—45)

This invention relates to an improved shoe construction and pertains more particularly to the structure of the counter and to the method of applying the same.

In the conventionally constructed shoe, the counter is a one-piece member cut from leather, pasteboard or the like, and then molded or partly molded to give it a predetermined contour designed to adapt the same to be used with a multiplicity of different sizes of lasts. To illustrate, there are only from five to ten different sizes of counters formed in this manner, depending upon the material they are composed of, while there are approximately one hundred and eighty different sizes of lasts that are commonly employed in the manufacture of shoes. It is, therefore, evident that while these counters will fit some of the lasts fairly closely, they will not accurately fit the greater majority thereof.

These preformed counters are first soaked in water to soften the same, and then mulled, and then they are inserted between the lining and the rear quarter of the shoe upper after which paste or cement is applied with a brush, cementing machine or the like upon the inner and outer surfaces of the counter. These combined members are assembled upon a last and then pulled over the last and side lasted. The shoe next goes to the flat bed lasting operator, who forms and tacks the heel seat to the last. Then the shoe is beaten with a maul or the like so as to mold the same in an endeavor more accurately to bring the counter into conformity with the contour of the last.

It will be understood that this method of procedure involves not only a considerable amount of time and labor, but often results in the finished shoe having an uneven interior surface due to the collection of cement at hollow places and the forming of air pockets between the counter and lining, which latter often results in a loose lining. These are prevalent in the conventional method of manufacturing shoes, as well as other defects, such as the counter becoming misplaced during the lasting operation, or the outer surface of the upper becoming soiled by the cement inadvertently coming in contact therewith.

It will, therefore, be seen that in the conventional method of forming counters and the application thereof, the perfection of the finished shoe depends very largely upon the ability or skill of the operator.

It is an object of this invention to provide a counter structure for boots, shoes and the like which may be more readily and successfully applied than herebefore.

Another object of the invention is to produce a counter of the above mentioned class which may be quickly and easily custom built for the last with which it is to be secured in place, whereby for each last there will be a specific counter 5 peculiarly adapted to perfectly fit the same.

Another object is to provide a counter as above described which becomes an integral part of the shoe upper and which, by reason of its perfect fit on the last, permits the shoe manufacturer to 10 use an upper a half size smaller than usual for a given last.

A further object of the invention resides in providing an improved method of applying the counter to the shoe upper whereby the counter 15 will be securely maintained in proper predetermined relation with the associated parts of the shoe, both during the lasting operation and after the construction operation has been completed.

Still another object of the invention is to provide a counter having an upper edge portion that is relatively flexible and which will not define a sharp line of demarcation when assembled in the shoe upper.

Other objects and advantages pertaining to the details of the structure of the counter and the manner of assembling the same in the shoe upper will more fully appear from the following description, taken in connection with the accompanying drawing in which:

Figure 1 is a plan view of one of the rear quarters of a shoe upper.

Figure 2 is a plan view of one of the sections of my novel counter.

Figure 3 is a plan view of the doubler or fabric backer for the quarter shown in Figure 1.

Figure 4 is a plan view illustrating the rear quarter shown in Figure 1, the doubler shown in Figure 3, and the counter sections shown in Figure 2 secured together.

Figure 5 is an enlarged detail sectional view taken on line 5—5, Figure 2.

Figure 6 is a perspective view, partially in section and with the inner shoe lining removed, illustrating the rear portion of a pair of rear quarters secured together by the back seam with the adjacent portions of the doubler and my novel counter connected thereto.

Figure 7 is a perspective view of a shoe upper embodying the various features of this invention 50 ready to be applied to the last and illustrating portions thereof broken away.

Figure 8 is an enlarged detail sectional view taken on line 8—8, Figure 7.

Figure 9 is an inner face view similar to Figure 55

6, illustrating a novel form of back seam reinforcing strip peculiarly adapted to be used with my improved counter.

Figure 10 is an enlarged sectional view taken 5 on line 10—10, Figure 9.

Figure 11 is a perspective view of the reinforcing strip illustrated in Figures 9 and 10 and showing the outer face thereof.

The shoe structure, as illustrated in the drawing, comprises primarily a pair of complementary rear quarters 10, a pair of doublers or fabric backers 11 for the quarters 10, the counter 12, vamp 13, and inner lining 14. The quarters 10 and backers 11 may be constructed in any well known manner, and as shown in Figures 1 and 3, are of substantially the same outline. These members are also nearly the same size, the only difference being that each doubler is slightly less in width from top to bottom than the corresponding quarter so that when the doubler is mounted upon the quarter, the top edge as 15 of the quarter will extend a short distance beyond the doubler to provide a marginal flange 15' which may be folded over the upper edge of the doubler as illustrated in Figure 4, to conceal the same and to provide a finished appearance to the upper edge of the shoe in the conventional manner. Also, the length of the doubler from the front edge 17 to the back edge 18 is slightly less than that of the quarter 10 whereby the rear edge of the quarter will project sufficiently beyond the doubler to provide a seam flange 20 for the stitches of the back or closing seam by which the quarters are secured to each other.

My novel counter 12 is composed of two similar sections 22 formed preferably from a material commonly known as celastic, comprising a body portion composed of fibrous material such as cloth or fabric impregnated with celluloid or other material that, after being cut or softened by the action of a solvent, becomes hard and rigid upon drying.

Although I preferably form the counter sections 22 from celastic or a similar material, it is to be understood that I do not wish to be limited to any one class of material, as I may readily form the sections from other materials such as leather, a manufactured product such as leatherboard, cardboard or the like.

Each pair of counter sections 22 is formed to be used with but one size of last. That is, for each last there is a specific pattern from which the counter is cut and formed so that each counter may be said to be custom built for a given last or the parts of the shoe formed thereon. To accomplish this result, each counter section 22 is formed with a bottom edge 23 which extends forwardly from the rear edge 24 in substantially a straight line and then curves outwardly or downwardly as at 23' to conform in contour and length to the bottom edge of the quarter 10, or more accurately to the doubler 11, while the rear edge 24 of each counter section conforms in outline substantially to the rear surface of the heel 16 of the last and, therefore, to the rear edge of the quarter and of the doubler.

The length of the bottom edge of the counter section is preferably substantially equal to that of the doubler, as illustrated in Figure 4, so that when the quarter, doubler and counter section are assembled together, the rear edges of the doubler and counter section will coincide, while the rear edge of the quarter will be spaced therebeyond to provide for the stitching flange 20 hereinbefore mentioned.

The distance from the bottom edge to the top edge of the counter section is preferably slightly less than that of the doubler so that when the counter section, doubler and quarter are assembled together, the counter section will lie a short distance below the marginal turned-over portion 15' of the quarter and the upper edge 25 of the counter section is preferably formed as illustrated in Figures 2 and 4 with the forward portion thereof curved or tapered inwardly as at 26 so as to meet the bottom edge 23 at the junction of said edge with the forward edge 17 of the doubler. The rear and top marginal edges of each counter section is beveled as at 27 by skiving or otherwise so that these portions are rendered much thinner in cross section than the remaining portion of the counter section and are correspondingly less rigid than the remaining portion thereof after the lasting operation.

The method of manufacturing the shoe upper 20 comprising this invention consists in first cutting out the rear quarters 10, the doublers 11, and the counter sections 22, after which the counter sections are skived as at 27 and then secured to the corresponding doubler or cloth backer 11 25 by means of stitching 29 with the bottom edge 23 and the rear edge 24 of the counter section substantially coinciding with the bottom and rear edges respectively of the doubler, as illustrated in Figure 4.

An adhesive, such as cement or paste is then applied to the inner surface of the outside quarter 10 or to the surface of the doubler opposite to that adjacent the counter sections or to both these surfaces, and the doubler and counter section are then mounted upon the outside quarter and secured thereto by the adhesive. This procedure is carried out with both the right and left quarter and then the quarters are secured together at their rear edges by stitching 30 in 40 the conventional manner, as illustrated in Figure 10.

The reinforcing tape as 31 is then rubbed on the back seam in the conventional manner after which the adjacent lower portions of the right and left quarters, the doublers and counter sections, together with the lower portion of the tape, are secured together by a cross stitching 32 in the manner illustrated in Figure 6, and thereby securing the counter sections at the lower rear ends to the adjacent portions of the outer quarters 10.

The top edge 15 of each outer quarter 10 is now folded over the adjacent portion of the corresponding doubler 11, as illustrated at 15', 55 Figure 4, and cemented thereto in the conventional manner. The vamp 13, which has previously been formed, is then secured to the front edge 16 of each of the outer quarter members 10 as by stitching 33, Figure 8.

It will be noted by referring more particularly to Figures 7 and 8, that the vamp piece 13 overlaps the adjacent edges of the quarters 10 so that the stitching 33 securing the vamp to the quarters extends downwardly over the forward end portion of each counter section 22, as illustrated at 34, Figure 7, and thereby provides additional means by which the counter sections are secured to the outer quarter 10.

It will now be observed that the counter sections 22 are not only securely fastened to the corresponding doubler or fabric backer 11 before the assembled shoe upper is placed on the last, but that these sections are also securely fastened at their front and rear portions adj- 75

cent the bottom thereof to the outside quarter 10 and will obviously be maintained in their proper relation with the associated portions of the shoe during the lasting operation.

5 After the vamp 13 has been thus secured to the outer quarters 10, the inner lining 14, which has previously been constructed in any well known manner, is then edged-in in the conventional manner by means of stitching 36 which 10 secures the upper edge only of the lining to the upper edge of the outer quarters 10. This assembled shoe upper is then ready to be placed upon a last, but before doing so the lining is folded back away from the counter sections, and 15 a suitable solvent is applied by spraying or otherwise to the inner surface of the sections sufficiently to soften the same, after which the lining is replaced and the upper is assembled or tacked on the last which it is to be lasted over. Inasmuch as the counter sections are 20 securely maintained in position, these sections will be pulled with a uniform tension on both sides of the last during the lasting operation and thereby assist the operator in maintaining the shoe members in proper relation to the 25 lines of the last.

Inasmuch as all portions of the upper may be firmly and tightly stretched over the last, there is less opportunity for the forming of wrinkles 30 in the lining of the shoe, particularly in the area of the counter. Furthermore, due to the close fitting of the upper to the last and particularly the pliable nature of the counter sections, the heel lasting machine will accurately register the 35 counter around the bottom of the last and produce a perfect heel seat.

Also, owing to the readiness with which this counter, when softened, conforms to the contour 40 of the last, there is very little resistance to the upper being pulled over the last, with the result that the top of the shoe will conform more accurately to the last and thus have an improved appearance. Moreover, as a result of the foregoing and of the accurate fit of the counter to 45 the last, the manufacturer, as pointed out above, is enabled to use an upper which is a half size smaller than is normal for a given last. Furthermore, when the counter is formed from a material such as celastic, which comprises a 50 fabric or the like impregnated with a stiffening substance such as celluloid that hardens after being softened by the action of a solvent, a certain amount of this stiffening substance will penetrate the doubler and adhere to the outer 55 quarter, and thus maintain the associated members in a fixed predetermined position which further acts in securing a good fit on the foot and in maintaining the shape of the shoe for an extended period.

60 It will be observed also, by referring to Figure 10, that owing to the counter being formed of two sections, slightly spaced at their rear edges adjacent the back or closing seam of the shoe upper, this seam will be imbedded into the 65 softened adjacent edges of the counter sections so that the curve of the back of the heel of the shoe and the back seam will conform to the contour of the last and present a smooth finished appearance.

70 The hereinbefore mentioned reinforcing tape 31 is of the usual construction comprising a canvas or fabric body coated at one side with a suitable adhesive which permits the member being readily secured to a surface by the application of pressure. These conventional reinforce- 75

ing members often become loosened at the edges and curl during use and thereby produce an uneven surface which irritates the foot.

In order to overcome this defect, I have provided a reinforcing member 40, peculiarly adapted to be used with my novel counter and which is illustrated more particularly in Figures 9, 10 and 11. This reinforcing member is composed preferably of the same material of which the counter sections are made. That is, it is preferably formed of celastic or similar material comprising a stiffening substance which, after being softened by a solvent, becomes stiff and rigid upon drying. This reinforcing member 40 comprises an upper relatively narrow portion 15 40' adapted to extend over the adjacent edge portions of the counter sections 22 and a lower portion 40'' of greater width adapted to extend some distance over adjacent portions of the counter sections at the lower edges thereof and 20 thereby further reinforce the same at the heel seat.

This reinforcing member 40 is preferably formed with the sides and upper end thereof beveled as at 41 by skiving or other suitable 25 means so that when applied to the shoe upper, it will form a smooth continuous surface across the inner face of the heel of the shoe from one side to the other, as shown in Figure 10. The reinforcing member 40 is applied after the upper 30 quarters have been closed by the back seam, as hereinbefore described for the reinforcing member 31, and is maintained in place until the upper is mounted on the last by the cross stitching 32 which is stitched in the manner previously de- 35 scribed.

Just before the assembled upper is placed on the last, the reinforcing member 40 is treated with a solvent together with the counter sections 22 so that during the lasting operation the material cut by the solvent will penetrate the members adjacent the reinforcing member 40 so that this reinforcing member is thereby firmly secured or welded to the adjacent members of the shoe upper, thus forming a shoe upper which, 45 after the material is dried and becomes hardened, is very rigid, particularly near the bottom and thus offers the maximum support for the heel of the foot.

In lieu of using the reinforcing member 40, 50 I may secure a similar result by elongating the counter sections 22 so that their back edges 24 extend slightly beyond the seam flanges 20 of the uppers 10. The stitching 29 in this case would be located as shown in Figure 4, thus leaving an unattached counter flap at the rear edge of each counter section which flap projects beyond the seam flange 20. These flaps would preferably be suitably skived, so that when the uppers are closed by the back seam 30, and flaps 60 can be separated and bent away from each other and would then lap against the bodies of the counter-sections 22 and form a smooth, double-thickness reinforcement serving somewhat the same function as the reinforcement 40. 65

Although I preferably form the shoe counter sections from a material such as celastic, as previously described, these sections 22 may as readily be formed from leather, prepared in the usual manner, with the exception that instead 70 of applying the adhesive to the leather just prior to the lasting operation, I preferably coat the leather sections before applying the same to the shoe upper with an adhesive which readily softens by the application of water and then, just 75

prior to the placing of the shoe upper on the last, I apply water to the leather counter and to the adhesive to soften the same in the same manner the solvent is applied when using the celastic material and thereby reduce the possibility of staining or defacing the outer surface of the quarters.

It is to be understood that irrespective of the material from which the counter sections are formed, the upper is permitted to remain upon the last until the solvent has evaporated and the members thereof have dried.

In Figure 7, I have illustrated the upper as being provided with wear piece 45 composed preferably of soft leather or the like and which is provided with a tab 45' which extends beyond the top edge of the upper. The wear piece 45 is preferably sewed to the lining around the edges of a hole formed therein. The tab 45' is utilized to receive therethrough the fastening means, such as a tack, not shown, for securing the upper to the last, thereby eliminating the necessity of puncturing the rear wall of the upper with the tack, as is customary in the prevailing method of manufacturing shoes. After the upper has been lasted and dried, the tab is cut off so as to leave the upper edge of the wear piece substantially flush with the upper edge of the shoe upper.

Although I have shown and particularly described the preferred embodiment of my invention, I do not wish to be limited to the exact construction shown, as various changes in the form and relation of parts thereof may be made without departing from the spirit of the invention as set forth in the appended claims.

I claim:

1. In a shoe structure of the class wherein a pair of complementary outer quarter sections are secured to each other at their rear ends by a back seam with the edges of said seam facing inwardly, in combination, a counter stiffener composed of two individual complementary sections, each of said stiffener sections being arranged in overlying relation with a respective one of the quarter sections, the rear ends of the counter stiffener sections being spaced from each other and receiving the inwardly facing edges of the back seam therebetween, means fixedly securing each counter stiffener section to said respective one of the outer quarter sections, a reenforcing element composed of counter stiffener material arranged to extend across said seam and in over-lying relation with the adjacent ends of said stiffener sections, and means securing the reenforcing element to the counter stiffener sections independently of said outer quarter sections.

2. A shoe upper of the class described comprising a pair of complementary outer quarter sections secured together by an inturned back seam, a counter stiffener composed of fibrous material and including two complementary members, each of said members having the lower edge and the rear edge thereof paralleling substantially the lower edge and the rear edge respectively of the quarter sections, means fixedly securing each counter stiffener member to a respective one of said quarter sections with the lower edge thereof substantially coincident with the lower edge of said quarter section and with the rear edges of said complementary counter stiffener members spaced apart to form a space for the back seam, the back seam stitches engaging the quarter sec-

tions only for securing said quarter sections together.

3. A shoe structure of the class described comprising an outer quarter section formed with the rear edge thereof convex so as to be adapted with a complementary section to conform substantially to the contour of the vertical center portion of the rear surface of the heel of a last, a counter stiffener member having its rear edge conforming to the contour of said rear edge of the quarter section, and means securing said counter stiffener member to the inner surface only of the quarter section with the rear edge thereof slightly spaced from said rear edge of the quarter section to form a margin on said quarter section adapted with the complementary margin to form a back seam.

4. A shoe upper of the class described comprising, in combination, two independent rear portions, a right hand portion and a left hand portion, each of said portions including an outer quarter section, one member of a two-part counter stiffener, and a doubler section mounted intermediate the outer quarter section and the counter stiffener member, means including a line of stitching extending along the rear, upper and forward edges of each member of the counter stiffener for securing the same to its respective doubler section, separate means securing each doubler section to the inner face of its respective outer quarter section, and means engaging the outer quarter sections only for securing said right and left hand portions to each other.

5. A shoe structure comprising an outer quarter section formed with the rear edge thereof convex so as to be adapted with a complementary section to conform substantially to the contour of the vertical center portion of the rear surface of the heel of a last, a doubler section having its rear edge conforming to the contour of said rear edge of the quarter section, means securing the doubler section to the quarter section with the rear edge thereof slightly spaced from said rear edge of the quarter section to form a margin on said quarter section adapted with the complementary margin to form a back seam, and a counter stiffener member secured to one of said sections and having the rear edge thereof substantially coincident with and conforming to said rear edge of the doubler section.

6. A shoe structure comprising an outer quarter section formed with the rear edge thereof convex so as to be adapted with a complementary section to conform substantially to the contour of the vertical center portion of the rear surface of the heel of a last, a doubler section having its rear edge conforming to the contour of said rear edge of the quarter section, means securing the doubler section to the quarter section with the rear edge thereof slightly spaced from said rear edge of the quarter section to form a margin on said quarter section adapted with the complementary margin to form a back seam, a counter stiffener member having the rear edge thereof substantially coincident with and conforming to said rear edge of the doubler section, the rear, upper and forward edges of said counter member being skived, and stitches engaging said skived edges securing the counter member to the doubler section.

7. In a structure for producing rear upper sections for shoes or the like, in combination, a pair of complementary outer quarter sections adapted to be secured together at their rear ends by a line of stitching to form a back seam, a pair of in-

dividual complementary flexible counter stiffener members, and means including stitching securing each of the counter stiffener members to a respective one of said quarter sections, said counter 5 stiffener members being composed of initially flexible material capable of being formed and stiffened in such form when moistened with a liquid, formed to shape and subsequently dried in such shape, whereby said counter stiffener members 10 may be readily secured to the quarter sections while in their flexible condition and may also be thereafter formed into and rendered efficacious as a counter stiffener after said quarter sections are secured together by the back seam 15 stitching..

8. A structure as in claim 7 having a relatively narrow reenforcing member having a relatively thick central portion extending longitudinally thereof and being tapered transversely from said 20 central portion outwardly to the longitudinal edges thereof, and means securing said reenforcing member to the shoe upper with the central portion of said member overlying the back seam and the longitudinal edges thereof in overlapping 25 relation with the adjacent portions of the counter stiffener members.

9. A structure as in claim 7 wherein the adjacent rear end portions of the counter stiffener members are beveled, and a reenforcing member 30 is secured over the back seam, said reenforcing member having the front surface thereof substantially flush with the adjacent front surfaces of the counter stiffener members to form a substantially smooth continuous surface extending 35 across said back seam from one of said counter stiffener members to the other.

10. In a structure for producing rear upper sections for shoes or the like, in combination, a pair of complementary outer quarter sections, a 40 pair of individual complementary flexible counter stiffener members spaced apart at their rear ends, means including stitching securing each of the counter stiffener members to a respective one of the quarter sections, each of said quarter sections being provided with a margin at the rear end 45 thereof extending inwardly between the spaced rear ends of the counter stiffener members, stitches engaging said margins for securing the quarter sections together to form a back seam; said counter stiffener members being composed of initially flexible material capable of being formed and stiffened in such form when moistened with a liquid, formed to shape, and subsequently dried 50

in such shape, whereby said counter stiffener members may be readily secured to the quarter sections while in their flexible condition, and may also be thereafter formed into and rendered efficacious as a counter stiffener after said quarter 5 sections are secured together by said stitches.

11. In a shoe structure of the class wherein a pair of complementary outer quarter sections are secured to each other at their rear ends by a back seam, a separate counter stiffener composed 10 of two complementary members, each of said members having the rear edge thereof juxtaposed to the back seam, means fixedly securing each counter stiffener member to a respective one of said outer quarter sections, a reenforcing element 15 composed of counter stiffener material arranged to extend across said seam and in overlying relation with the adjacent ends of said counter stiffener members, and means securing the reenforcing element to the counter stiffener 20 members independently of said outer quarter sections.

12. A shoe structure as in claim 11, wherein the overlying edge portions of the counter stiffener members and the reenforcing element are 25 beveled, whereby the reenforcing member forms a smooth continuous surface from one counter stiffener member to the other.

13. In a shoe structure of the class wherein a pair of complementary outer quarter sections are 30 secured to each other at their rear ends by a back seam, and a lining for said sections extends across said seam, a separate counter stiffener mounted intermediate the lining and said quarter sections, said counter stiffener being composed of two complementary members, each of said members having the rear edge thereof juxtaposed to the back seam, means fixedly securing each counter stiffener member to a respective one of said outer quarter sections, a reenforcing element composed 40 of counter stiffener material interposed between the lining and the counter stiffener members in overlying relation with the adjacent ends of said counter stiffener members, and means securing the reenforcing element to the counter stiffener 45 members.

14. A shoe structure as in claim 13 wherein the overlying edge portions of the counter stiffener members and the reenforcing element are beveled, whereby the reenforcing element forms a smooth 50 continuous surface from one counter stiffener member to the other.

JAMES F. MARSHALL.
